UNITED STATES PATENT OFFICE.

FRANK E. SUMMERS, OF MEMPHIS, MISSOURI.

ELECTRICAL SIGNALING APPARATUS.

1,265,698.

Specification of Letters Patent. Patented May 7, 1918.

Application filed February 12, 1917. Serial No. 148,058.

To all whom it may concern:

Be it known that I, FRANK E. SUMMERS, a citizen of the United States, residing at Memphis, in the county of Scotland and State of Missouri, have invented certain useful Improvements in Electrical Signaling Apparatus, of which the following is a specification, reference being had therein to the accompanying drawing.

10. This invention relates to improvements in electric signaling apparatus, one object of the invention being the provision of an apparatus of this type which is adapted for giving audible signals as a telephonic or 15 telegraphic receiver or as a signaling horn for vehicles, such for instance as motor cars or locomotives.

A further object of this invention is the provision of a device of this character in 20 which the diaphragm is under the control of oppositely disposed permanent magnets of the horse-shoe type while each pole of the respective magnets has connected thereto so as to influence the same a coil, all of 25 said coils being in circuit and adapted to be effected by a source of alternating or vibrating current so as to produce in the diaphragm a vibration.

A still further object of this invention is 30 the provision of an adjustable tuning means for one of the armatures connected to the diaphragm so that the diaphragm may be tuned at will.

With the foregoing and other objects in 35 view and which will appear as the description proceeds, the invention resides in the novel arrangement and combination of parts hereinafter set forth and claimed, it being possible to make many changes in the precise embodiment without departing from the 40 spirit of the invention.

In the accompanying drawings:

Figure 1 is a longitudinal sectional view 45 through the horn and its casing having the present diaphragm effecting arrangement disposed therein.

Fig. 2 is a front view of the diaphragm and one of the magnet supports the magnet also being shown in elevation.

50 Referring to the drawings, the numeral 5 designates an attaching plate by means of which the present device may be connected to any desired structure as an automobile, motor car or locomotive, there being connected thereto the oppositely disposed arms 6 and 7 which support respectively the rear

member 8 and the amplifying member 9 of the present horn.

Mounted so that its periphery is properly clamped between these members is a diaphragm 10 which as shown in Fig. 2 is provided with openings 11 therethrough so that as will presently appear, the sound waves generated upon the side opposite the member 8 may have passage therethrough to the 65 amplifying member 9.

Attached to opposite sides of the diaphragm concentric thereof are the two blocks 12 and 13 to which are connected the screws 14 and 15 for attaching the armatures 70 16 and 17 to the diaphragm, the purpose of which will presently appear. The armature 17 is extended so as to be fulcrumed at 17' between the members 8 and 9 having the resilient extension 18 which forms a tuning 75 device or rod having mounted thereon the adjustable weight 19 through the instrumentality of the screw 20.

80 Mounted between the members 8 and 9 upon the side of the diaphragm adjacent to the member 9 is a support 21 for the permanent horse-shoe magnet 22 whose poles are disposed in attractive relation to the armature 16 while connected by screws 23 to the member 8 is the permanent 85 horse-shoe magnet 24 whose poles are supported in a support 25 which is similar to the support 21, but which may be dispensed with if so desired as the screws 23 may be ample in supporting the magnet 24. Thus 90 the poles of the magnet 24 are disposed in attractive relation to the armature 17.

The conductors 26 are adapted to be connected to a series of alternating or vibrating current and are so constructed and arranged 95 as to connect the coils 27, 28, 29 and 30 in series so that when the current is flowing through the conductor 26 and consequently these coils, a vibration is set up through the armature 16 and 17 to the diaphragm 10 so 100 that sound is generated.

With this construction of audible signal device, the magnets 22 and 24 and the other parts being practically in fixed relation to each other, it is simply necessary to adjust 105 the weight 19 of the resilient rod 18 and thus tune the diaphragm as desired.

From the foregoing description it is evident that an exceedingly simple and efficient audible electric signaling device is provided, 110 the same being so constructed and arranged as to be readily attached for use upon auto-

mobiles and locomotives for giving an audible alarm or to be connected for telephonic or telegraphic purposes it being a loud talking amplifying device so that telephonic or telegraphic signals may be received without the necessity of placing the device to the ear.

Although the coils in the present instance have been shown connected in series it is possible to connect them in multiple or 10 bridging them as may be desired.

It is also possible to dispense with one of the horse-shoe magnets and use the one in the rear of the diaphragm while it is also possible to dispense with the armatures 15 which are connected to the diaphragm so that one or more of the horse-shoe magnets influence directly the diaphragm. In this case the magnetic circuit is directed through the diaphragm.

20 What I claim as new is:

1. A signaling device including a support, a diaphragm mounted therein, two armatures connected to opposite sides of the diaphragm, two permanent magnets mounted 25 upon opposite members to the diaphragm in attractive relation to the armatures, and a plurality of connected coils disposed upon the poles of the permanent magnets, one of the armatures being extended and having a 30 fulcrumed resilient tuning terminal.

2. A signaling device including a support, a diaphragm mounted therein, two armatures connected to opposite sides of the diaphragm, two permanent magnets mounted 35 upon opposite members to the diaphragm in attractive relation to the armature, a plurality of connected coils disposed upon the poles of the permanent magnets, one of the armatures being extended and having a ful- 40 crumed resilient tuning terminal, and an adjustable means upon said terminal for adjusting the tuning effect thereof.

3. An electric signaling device including a two part casing having an open amplifying member, a perforated diaphragm disposed between said members, two armatures connected upon opposite sides of and to the diaphragm, two double poled permanent magnets mounted upon opposite sides of 50 the diaphragm and in attractive relation to the respective armatures, a plurality of electrically connected coils mounted upon the poles of said permanent magnets, and a resilient fulcrumed tuning terminal having 55 one of said armatures disposed exteriorly of the casing.

4. An electric signaling device including

a two part casing having an open amplifying member, a perforated diaphragm disposed between said members, two armatures connected upon opposite sides of and to the diaphragm, two double poled permanent magnets mounted upon opposite sides of the diaphragm and in attractive relation to the respective armatures, a plurality of electrically connected coils mounted upon the poles of said permanent magnets, a resilient fulcrumed tuning terminal having one of said armatures disposed exteriorly of the casing, and an adjustable weight mounted 70 upon said terminal.

5. An electric signal device including a two member casing one of which is an amplifying horn, a diaphragm having its periphery supported between said members and 75 said diaphragm being provided with perforations, two armatures one upon each side of the diaphragm connected to the center of the diaphragm, two horse-shoe magnets disposed to have their poles in attractive relation to the respective armatures, one of the magnets being supported in one member of the casing, a support for the other member having its terminals connected between the diaphragm and the amplifying member, a plurality of electrically connected coils mounted 80 upon the poles of said magnets, and a resilient fulcrum terminal for one of the armatures projecting exteriorly of the casing, and forming a tuning device for the diaphragm. 90

6. An electric signal device including a two member casing one of which is an amplifying horn, a diaphragm having its periphery supported between said members and 95 said diaphragm being provided with perforations, two armatures one upon each side of the diaphragm connected to the center of the diaphragm, two horse-shoe magnets disposed to have their poles in attractive relation to the respective armatures, one of the magnets being supported in one member of the casing, a support for the other member having its terminals connected between the diaphragm and the amplifying member, a plurality of electrically connected coils 100 mounted upon the poles of said magnets, a resilient fulcrumed terminal for one of the armatures projecting exteriorly of the casing, and forming a tuning device for the diaphragm, and an adjustable weight 110 mounted upon said terminal.

In testimony whereof I affix my signature.

FRANK E. SUMMERS.
